UNITED STATES PATENT OFFICE.

ALBERT VON STEINER GÖLTL AND JACOB BAUMGARTNER, OF WASHINGTON,
DISTRICT OF COLUMBIA.

DESIGN FOR A FINGER RING.

Application filed July 1, 1925. Serial No. 13,972. Term of patent 7 years.

To all whom it may concern:

Be it known that we, ALBERT VON STEINER GÖLTL and JACOB BAUMGARTNER, both citizens of the United States, residing at Washington, in the District of Columbia, have invented a new, original, and ornamental Design for Finger Rings, of which the following is a specification, reference being had to the accompanying drawing, forming a part thereof.

Fig. 1 is a plan view; and
Figs. 2 and 3 are, respectively, side and end elevations of the finger ring embodying our new design.

We claim:

The ornamental design for a finger ring as shown.

ALBERT VON STEINER-GÖLTL,
JACOB BAUMGARTNER,
